UNITED STATES PATENT OFFICE.

HUGO COOK, OF DAYTON, OHIO.

CASH INDICATOR AND REGISTER.

SPECIFICATION forming part of Letters Patent No. 473,694, dated April 26, 1892.

Application filed February 5, 1892. Serial No. 420,411. (No model.)

To all whom it may concern:

Be it known that I, HUGO COOK, a citizen of the United States, residing at Dayton, in the county of Montgomery and State of Ohio, have 5 invented certain new and useful Improvements in Cash-Registers, of which the following is a description, reference being had to the accompanying drawings, forming part of this specification.

10 My invention relates to machines of the general character of those shown and described in my patents, Nos. 469,544 and 469,545, of February 23, 1892, in which machines the indicator and registering wheels each revolve 15 in one direction only and are actuated by a driver which likewise revolves in one direction only.

My present invention consists in new combinations, constructions, and arrangements of 20 parts incident to the further development of the machines shown in my aforesaid patents, all as will be hereinafter set forth, and specifically pointed out in my claims.

In the accompanying drawings, Figure 1 25 represents a front elevation of my improved machine; Fig. 2, a rear elevation thereof with the rear side of the casing removed; Fig. 2^a, an enlarged rear elevation of the driver; Fig. 3, a vertical central section of the machine 30 on the line 3 3 of Fig. 2, looking toward the right of the machine in that view; Fig. 3^a, a vertical section of the driver, showing a rear view of the cam-groove in its front side. Fig. 3^b is a detail view of one of the keys or stops. Fig. 4 is a vertical section of the machine 35 without the base on the line 4 4 of Fig. 3, looking toward the front of the machine; Fig. 5, a corresponding view on the line 5 5 of Fig. 3; and Figs. 6 and 7, similar views, on 40 the line 6 6 and 7 7 of Fig. 3, respectively.

The same letters of reference are used to indicate identical parts in all the figures.

The principal working parts of the machine are inclosed in a circular casing A, supported 45 in an upright position upon a suitable base B. A central shaft C is journaled in the front wall of the casing and in a bearing supported in rear of said wall, as hereinafter explained. This shaft is revoluble in the direction of the 50 arrow and has secured upon its front end a handle D for turning it, Fig. 1. Upon the opposite or rear end of the shaft C, Figs. 2,

3, and 2^a, is secured what I term the "driver," consisting of a disk E, provided on its rear face with cam-grooves and with a diametrical 55 guideway, in which fits a sliding plate, to be presently described. This disk E is fast upon the shaft C and turns with it. Between the disk and the front wall of the casing are mounted upon or concentric to the shaft C 60 various wheels, disks, cams, &c., as shown in the sectional view in Fig. 3. Immediately to the left of the disk E in said figure is a toothed wheel F, Fig. 7, fast upon the rear end of a sleeve G, which is loose on the shaft C and 65 extends to the left in Fig. 3 toward the front wall of the casing, and has keyed upon its front end a large gear-wheel H and a toothed locking disk or ratchet I, Fig. 5. The wheel H is the driving-gear for the primary registering-wheel, whose pinion J meshes with the gear H, as shown in Fig. 5.

Next to the left of the toothed wheel F, Fig. 3, is a radially-sliding bar or plate K, Fig. 7, having an elongated slot at its middle, 70 through which the shaft C and sleeve G pass. Secured upon the right hand or rear face of this bar K, upon opposite sides of the central shaft, are two lugs or sets of teeth LL', which alternately co-operate with the toothed wheel 75 F to drive the register in the manner hereinafter explained. Also projecting from the rear face of the bar K, beyond the vertical plane of the teeth LL', is a stud M, which fits in a cam-groove L² in the forward side of the driver 80 E, the shape of which groove is shown in Fig. 3^a.

Next to the left of the bar K, Fig. 3, is a large gear-wheel N, Figs. 6 and 7, loose upon the sleeve G. This gear is provided upon diametrically-opposite sides of its center with two radial slots L³ and L⁴, Fig. 6, through 90 which extend two studs O O', projecting from the front face of the bar K, Fig. 3, so that the bar and gear-wheel must revolve together, 95 while the bar is free to reciprocate diametrically of the wheel. The front ends of the studs O O' project beyond the front face of the wheel N and are beveled off to form teeth which co-operate with a toothed locking-disk 100 P, Figs. 6 and 7, which is fast upon the rear end of a sleeve Q, surrounding the sleeve G and keyed at its front end to a bracket composed, mainly, of two supporting-arms R R, se-

cured to the rear side of the front wall of the casing, Fig. 5. The toothed disk P thus being fixed, it will be understood that when either one of the studs O O' upon the bar K 5 is engaged with a notch in it, as the upper lug O is in Figs. 3 and 7, said bar and the wheel N will both be positively locked from movement.

Next to the left of the locking-disk P, Fig. 10 3, and loose upon the sleeve Q is a gear-wheel S, which is fast upon the rear side of the large indicator-wheel T. This gear-wheel is shown in dotted lines in Fig. 6. The numbers on the forward face of the indicator-wheel T are arranged to be exposed singly at a reading-opening T' in the front wall of the casing. The gear-wheel N, heretofore described, meshes with a small pinion N', Figs. 2, 6, and 7, fast upon a shaft journaled in a bracket N², 15 cured to the casing at the right of the wheel N, and a larger pinion N', fast on the same shaft as the pinion N', meshes with the gear S, fast upon the indicator-wheel T, so that the movements of the gear N are thus transmitted to the gear S and indicator T.

Next to the left of the indicator-wheel T, Fig. 3, is the bracket R, Fig. 5, heretofore described, this bracket forming the second bearing and support for the shaft C, referred to 30 at the beginning of the specification.

Next to the left of the bracket R are the gear-wheel H and toothed locking-disk I, Fig. 5, both fast upon the front end of the sleeve G, as heretofore described, so that the movements of the toothed wheel F, which is keyed 35 to the opposite rear end of said sleeve adjacent to the driver E, are transmitted through the sleeve G and gear H to the register, the primary wheel J of which is shown in Fig. 5.

Next to the left of the locking-disk I, Fig. 40 3, is a plate or bar U, Fig. 4, mounted upon the shaft C by an elongated slot at its right-hand end and by a similar slot upon a screw-stud V upon the casing near its left-hand end. 45 This bar has projecting from its rear face a lug W, which co-operates with the toothed wheel I, as indicated by the dotted lines in Fig. 5. A stud X, projecting from the forward face of the bar, fits in a cam-groove Y 50 in the rear face of a revoluble disk Z, fast upon the shaft C. As the disk Z revolves, the bar U is slid toward and from the shaft C and the lug W engaged with and disengaged from the ratchet I. When it is engaged with 55 the ratchet, it will lock the same and the gear H and register from movement, as herein-after explained.

Next to the left of the bar U on the shaft C, Fig. 3, is a second bar A', extending toward 60 the right-hand side of the machine in Figs. 4 and 5. This bar is mounted upon the shaft by an elongated slot at its left-hand end and upon a screw-stud A² by a similar slot near its right-hand end. A stud A³ upon the front 65 side of this bar fits in a second cam-groove Y' in the disk Z, by which means the bar is given a reciprocating movement as the shaft

C and disk Z revolve. The purpose of the bar A' is to actuate the detent-plate B' to release the operated key at the completion of 70 each revolution of the handle and driver. This curved detent-plate is mounted by slots upon screw-studs at B², Figs. 4 and 5, so as to be capable of reciprocating in the arc of a circle concentric to the shaft C. A spring B³, 75 connected to the upper left-hand end of the plate B', yieldingly holds it in and restores it to normal position. The keys C' are arranged in two rows concentric to the shaft C and pass through slots in the plate B'. They are carried in tubular housings C² upon the front face of the casing and their extreme rear ends

pass through and are supported and guided in holes in a fixed plate C³, Figs. 2 and 3. Surrounding each key within its housing C² is a 80 coiled resetting-spring C⁴, bearing at its outer end against a shoulder on the key and at its inner end against the bottom of the bore, which is made in the front wall of the casing coincident with the bore of the housing. The large 85 bore does not extend quite through the wall of the casing; but a smaller one extends through the remaining thickness and permits the passage of the key and at the same time forms a shoulder at the bottom of the large bore, 90 against which the inner end of the spring C⁴ may bear, as seen in Fig. 3. The stems of the keys are of the shape shown in Fig. 3' and are provided with shoulders C⁵, which co-operate with the detent-plate B'. When a key 95 is pushed in, its spring C⁴ is compressed, and its shoulder C⁵ pushes the plate B' aside as it passes, after which the plate springs back toward normal position behind the shoulder and detains the key in its inner position. 100 Pins C⁶, passed through and projecting from the sides of the keys, bear against the rear face of the wall of the casing when the keys are in their normal position and hold the keys in place against the pressure of the springs C⁴. 105

A stud B⁴ upon the upper right-hand end of the plate B', Figs. 2, 4, and 5, rests in a notch in the upper side of the bar A'. The right-hand side A⁴ of this notch is inclined or beveled, so that when the bar is slid to the 110 left toward the center of the machine the incline A⁴, riding under the stud B⁴ on the plate B', will lift that end of the plate against the resistance of the spring B³ at its opposite end. This movement of the plate will carry 115 it from behind the shoulder of any key which may have been pushed in and caught by it, and the key will thereupon be thrown out to normal position by its spring. Now owing to the shape of the cam-groove Y' in the disk Z, with which groove the stud A³ on the bar A' co-operates, the bar A' will be slid toward the center of the machine and the detent-plate B' be moved, in the manner described, just before the operating-handle and driver 120 complete their revolution and come to normal position, so that the operated key is released and restored to normal position at the end of each operation of the machine. The 125

cam-groove Y' holds the bar A' to the left but an instant and moves it to the right again and permits the plate B' to be reset by the time the handle and shaft reach normal position, so that when another key is pressed in preparatory to the next operation of the machine the plate B' will be in position to engage the shoulder of the key. A portion of the periphery of the disk Z is cut away, as seen in Fig. 4, to form a shoulder at Z'. This shoulder co-operates with one end of a bent arm Z², pivoted to the bar A', the other end of said arm fitting in a slot in an upward extension B⁵ of the plate B'. When the parts are all in their normal position, the left-hand end of the arm Z² lies in the path of travel of the shoulder Z' and locks the machine from operation. When, however, any key is pressed inward and the detent-plate B' thereby moved to the right and its right-hand end thrown upward, the right-hand end of the arm Z² is carried with it and the left-hand end of the arm thrown downward, out of the path of the shoulder Z', and the disk Z is then free to be turned forward. When a key is pushed in until its shoulder passes the detent-plate, the latter, in catching behind the shoulder, is not permitted to return all the way to normal position, owing to the fact that the portion of the key behind its shoulder is thicker than that in front of it, as seen in Fig. 3^b. After a key is pushed in, therefore, the locking-arm Z² is held out of the path of the shoulder Z' until the shaft and disk Z are given nearly a complete revolution and the plate B' so moved by the stud A⁴ on the bar A' as to release the key, in the manner before explained, the locking-arm being thrown up in front of the shoulder just before the parts come to rest in normal position.

The periphery of the disk Z is provided with ratchet-teeth, which co-operate with a pawl F' to prevent backward movement of the disk and shaft.

Upon the front face of the disk Z is a notched cam Z³, (shown in dotted lines in Fig. 4,) co-operating with a screen-plate Z⁴, arranged to vibrate back and forth between the indicator-wheel T and the reading-opening T' in the front wall of the casing to alternately hide and expose the numbers on said wheel. This screen is pivoted to the casing at Z⁵, and its lower end co-operates with the cam Z³. When the notch in the cam is brought into position for the lower end of the screen-plate to enter it, a spring Z⁶, connected to the plate, will pull the upper end of the plate to the left away from the reading-opening, and expose the number on the wheel T, which may then be behind the opening. When the disk Z is turned forward, however, the periphery of the cam Z³ bearing against the lower end of the plate Z⁴, will throw the screen to the right behind the reading-opening and hold it there until the notch in the cam again comes around into

position for the lower end of the plate to spring into it. When the operating-handle and other parts of the machine are in their normal position of rest, the notch in the cam Z³ stands in position for the end of the plate Z⁴ to engage it, and the screen is held by the spring Z⁶ to the left of the reading-opening to expose a number on the indicator T. When the operating-handle is started forward at the beginning of an operation, the cam Z³ at once throws the screen behind the reading-opening, and the numbers on the indicator-wheel which pass behind said opening are hidden until the handle reaches normal position again, whereupon the screen is pulled to the left by its spring and the proper number on the indicator exposed to view.

As heretofore stated, the driving-disk E at the rear of the machine, Figs. 2 and 2^a, is provided upon its rear face with two eccentric semicircular grooves G¹ and G² and a radially-sliding plate G³, fitting in a suitable guide-way in the disk. These grooves and this sliding plate co-operate with two lugs H¹ and H², projecting into the grooves from the inner face of a latch-bar I', Figs. 2^a and 3 and dotted lines in Fig. 2. This bar extends diametrically across the machine and is suitably bent or shaped to fit over the driver E and have its opposite ends fit against the rear face of the bar K, heretofore described and as seen in Figs. 2 and 3. The opposite ends of the bar I' are provided with slots which embrace lugs I² on the rear face of the bar K, Figs. 2, 3, and 7, and the heads of screws I³, entering the lugs, secure the bar I' to the bar K. The two bars thus must revolve together, but are free to reciprocate independently of each other.

Upon the front face of the bar K, near its opposite ends, Fig. 3 and dotted lines in Figs. 7, are two lugs O³ and O⁴, which co-operate with a shoulder N⁵ on the inner face of a lug N⁴, secured upon the bracket N², Figs. 2, 6, and 7, in the manner hereinafter explained.

It will be remembered that the bar K has upon its front face two studs O and O', Fig. 3, which project through slots in the gear-wheel N, which drives the indicator, Figs. 6 and 7, so that the bars K and I' will therefore both revolve with the wheel N. Upon the inner face of one end of the bar I' are two cams J' and J², Figs. 2 and 3, and upon the inner face of its opposite end two similar cams J³ and J⁴. These cams co-operate with the rear ends of the keys C', the cams J' and J⁴ with the keys of the outer row, and the cams J² and J³ with the keys of the inner row. The cams J² and J³ also co-operate with the outer side of the lug N⁴ on the bracket N², all as hereinafter explained.

In Fig. 2^a is shown a full-sized rear view of the driver E, a portion of the latch-bar I' being shown in dotted lines, and its lugs H¹ and H², fitting in the grooves G¹ and G² in section. It will be seen that the outer wall of the groove G² at the right-hand side of the

- disk terminates in two shoulders K' and K^2 , so that as the disk turns in the direction of the arrow the lug H' in the groove G' must pass both of these shoulders before it can enter the groove G^2 . So at the left-hand side of the disk the inner wall of the groove G' terminates in two shoulders K^3 and K^4 , both of which must be passed by the lug H^2 in the groove G^2 before it can enter the groove G' .
- Upon the right-hand end of the sliding plate G^3 are two teeth M' and M^2 . This plate is pressed toward the right in Figs. 2 and 2^a and yieldingly held in the position shown by a coiled spring G^4 , interposed in a recess formed in the side of the plate at the left of its middle, the spring bearing at one end against the plate and at its other against the base of the shoulders K^3 and K^4 . Near its left-hand end the plate G^3 is provided with a transverse slot G^5 , which normally registers with the end of the groove G^2 , but may be made to register with the end of the groove G' when the plate G^3 is slid toward the left and the spring G^4 compressed.
- The operation of the machine is as follows, assuming the parts to be in the position shown in the drawings, in indication of a previous sale of fifty-five cents: As the driver E is turned with the operating-handle and central shaft in the direction of the arrows in Figs. 2 and 2^a and the first tooth M' at the right-hand end of the plate G^3 comes in contact with the lug H' on the bar I' , that end of the plate will be forced slightly inward against the resistance of the spring G^4 until the tooth passes the lug, whereupon the plate will spring back to normal position and the lug will be caught between the teeth M' and M^2 with its upper rear face in contact with the shoulder K' of the driver. At this moment, also, the cam-groove L^2 in the forward side of the driver, Fig. 3^a, acting on the stud M of the bar K , Figs. 3 and 7, will lift said bar from the position shown in Figs. 3 and 7 and disengage its teeth L from the registering-wheel F . The bar I' (and with it the bar K and the gear-wheel N , which drives the indicator) being now locked to the driver E by the lug H' , as the driver continues to revolve these parts are carried around with it until the cam J^3 upon the inner face of the lower end of the bar I' in Fig. 2 reaches the lug N^4 on the bracket N^2 . As the cam J^3 rides over the outer side of the lug N^4 , the bar I' will be drawn toward that side of the machine and the lug H' on the bar will pull the plate G^3 in the same direction against the resistance of the spring G^4 far enough to permit the lug to clear the shoulder K' . At this moment the lug O^4 upon the inner face of the lower end of the bar K , Figs. 3 and 7, will come in contact with the shoulder N^5 on the lug N^4 . This will momentarily arrest the bars K and I' and the driver will turn slightly forward independently of them. This independent movement of the driver will carry the second tooth M^2 on the end of the plate G^3 past the lug H' , and the

latter will then abut against the shoulder K^2 and be confined between said shoulder and the tooth M^2 . This independent forward movement of the driver, while the bar K is caught on the shoulder N^5 , serves another purpose. It causes the cam-groove L^2 in the forward side of the driver, Fig. 3^a, acting on the stud M of the bar K , to draw said bar toward the left and engage its teeth L' with the registering-wheel and at the same time carry the lug O^4 out of engagement with the shoulder N^5 to release the bar and permit it to move on forward. The driver is thus connected to the register, so that from this point forward it drives both the indicator and register. The end of the bar I' which carries the cams J' and J^2 now begins to travel over the rows of keys C' , and when the key whose rear end has been thrown into the path of travel of the cam J' or J^2 is reached the outer face of the cam will ride over the inner face of the key and the bar I' will be forced upward away from the key until the abrupt shoulder or heel O^2 of the cam engages the key and positively arrests the bar. This upward movement of the bar causes its lug H' , which has been confined between the tooth M^2 on the plate G^3 and the shoulder K^2 on the driver, to press the plate upward far enough to permit the lug to clear the shoulder K^2 and enter the groove G^2 , the lug H^2 at the opposite side of the driver having cleared the shoulders K^3 and K^4 and simultaneously entered the groove G' . The lug H' now being in the groove G^2 and the lug H^2 in the groove G' , the driver is free to turn onto normal position independently of the bar I' and connected parts, which remain at the point at which they were arrested by the operated key. At the moment that the bars I' and K are arrested by the operated key and the driver begins to move forward independently of them the action of the cam-groove L^2 in the front face of the driver upon the stud M on the bar K will draw the bar downward, more deeply engaging its teeth L' with the notches in the wheel F , as shown in the case of the teeth L in Fig. 7, and at the same time engaging the extreme forward end of the lug O' on the front side of the bar K (in front of the gear-wheel N , Fig. 3) with a notch in the locking-disk P , which, it will be remembered, is fast upon the rear end of a fixed sleeve Q , carried by the bracket R . This engagement of the lug O' with the locking-disk P positively locks both the bars I' and K and the indicator and register from movement, and they remain so locked until the beginning of the next operation of the machine, whereupon they are released in the following manner: As the driver turns forward from normal position at the moment or just before the toothed end of the plate G^3 reaches the lug H^2 , which is then standing in its path, the cam-groove L^2 in the front side of the driver, acting on the stud M on the bar K , lifts said bar, and not only disengages the lug O' from the locking-disk

P, but also disengages the teeth L' from the wheel F, which drives the register, so that the bars I' and K and the gear N, which drives the indicator, are then free to turn forward with the driver without the wheel F and register. To prevent any accidental turning forward of the wheel F and register, however, I provide the lock shown in Figs. 4 and 5, where, it will be remembered, a locking-tooth W, upon the rear side of a bar U, co-operates with a ratchet I, fast upon the front side of the gear H, which drives the register. A stud X, upon the forward side of the bar U, co-operates with a cam-groove Y in a disk Z, and the shape of said groove is such that the bar U is drawn inward and the tooth W engaged with the ratchet I at the beginning of the forward movement of the driver from normal position and holds it in this locking position until the driver has made half of a revolution, whereupon the bar U is thrown outward again, the tooth W disengaged from the ratchet I, and the registering-wheel released.

Having described above the operation of the various parts in detail, it will, perhaps, make it clearer to describe it more generally and briefly as follows: With the parts in the position shown in the drawings some one of the operating-keys is first pushed in and caught by the detent-plate B', Figs. 3, 4, and 5. This will move the detent-plate upward to the right in said figures and throw the locking-arm Z² out of the path of the shoulder Z' on the disk Z to permit the latter and the operating-handle to be moved forward. The handle is then started forward and the cam Z³ on the forward face of the disk Z at once throws the screen-plate Z⁴ to the right and closes the reading-opening T'. The cam-groove Y in the disk Z, acting on the stud X of the bar U, then moves the locking-tooth W into engagement with the ratchet I and locks the register. Just before the toothed end of the plate G³ and shoulder K' of the driver, Figs. 2 and 2^a, reach the lug H' on the bar I' and pick up said bar to carry it and the bar K and gear N forward with the driver the cam-groove L² in the front side of the driver, acting on the stud M of the bar K, lifts said bar and disengages the lug O from the locking-disk P and the teeth L from the register-wheel F. The driver then carries the bars I' and K and gear-wheel N on around with it. When the driver has completed one-half of a revolution and the lower end of the bar I' has been carried around until its cam J³ engages the outer side of the lug N⁴, the indicator has been brought to zero or initial position. At this point the cam-groove Y in the disk Z, Figs. 4 and 5, moves the bar U to the left again and disengages the tooth W from the ratchet I to release the register. As the cam J³ on the bar I' rides over the outer side of the lug N⁴, Fig. 2, the bar is drawn to the right and the lug H' moved out of engagement with the shoulder K' of the driver, Fig. 2^a. The lug

O⁴ on the forward side of the lower end of the bar K then comes in contact with the shoulder N⁵ on the lug N⁴ and momentarily arrests the bars I' and K, while the driver moves on without them far enough to carry its shoulder K' and the tooth M' on the plate G³ past the lug H' and engage the shoulder K² with said lug, and also to cause the cam-groove L² in the front side of the driver to draw the bar K to the left far enough to disengage its lug O⁴ from the shoulder N⁵ on the fixed lug N⁴ and to engage its teeth L' with the register-wheel F. The lug O⁴ on the bar K having now cleared the shoulder N⁵, the driver carries the bars K and I' and the indicator and register forward with it, moving the indicator from zero or initial position to the new indication and adding the amount 85 upon the register. When the end of the bar I', which carries the cams J' and J², which is now traveling over the rows of keys C', reaches the operated key, (whose rear end will stand in the path of one of the cams J' or J²), the cam will ride over the key and lift the bar K, disengaging its lug H' from the shoulder K² of the driver, and as the shoulder O² at the heel of the cam strikes the key and positively arrests the bar I' the driver moves 90 on alone. At the beginning of the independent movement of the driver the cam-groove L² in its forward side, acting on the stud M of the bar K, will draw down the bar K to the position shown in Fig. 7 and engage its lug 100 O' with the locking-disk P, Fig. 3 and in dotted lines Fig. 7. Just before the driver reaches normal position, the cam-groove Y' in the disk Z, Figs. 4 and 5, acting on the stud A³ of the bar A', draws said bar to the left; 105 and the incline A⁴, riding under the pin B⁴ on the detent-plate B', lifts said plate and releases the operated key, whose spring immediately throws it out to normal position. The cam-groove Y' then moves the bar A' to the 110 right again, the spring B³ resets the detent-plate B', and the locking-arm Z² is moved into the path of the shoulder Z' on the disk Z, while the notch in the cam Z³ on the front side of the disk Z comes under the lower end 115 of the screen-plate Z⁴ as the parts reach normal position, and the spring Z⁶ draws the screen Z⁴ away from the reading-opening T' to expose the new indication. As before stated, when the cam J' or J² on the bar I' comes in contact with the operated key it rides over the key and lifts the bar I' until the shoulder O² at the end of the cam strikes the key. This positively arrests the bar and the driver moves on alone, leaving the shoulder of 120 the cam caught upon the key. As the driver begins its further independent movement, however, the cam-grooves G' and G², owing to their eccentric position in the driver, will lift the bar I' and carry the shoulder O² of the engaged 125 cam above the line of the row of keys, as seen in Fig. 2, so that at the next operation of the machine said cam and shoulder can travel freely above the row of keys, and thereby clear 130

- the operated key if it should happen to be one to the right of the bar in said figure. As shown in the drawings, the gear N, which revolves with the bars K and I' and drives the indicator, has sixty teeth. The gear N', with which it meshes, has twenty teeth; the gear N², on the same shaft as the gear N thirty-two teeth, and the gear S, fast on the indicator-wheel T, forty-eight teeth, so that the wheel
- 5 10 15 20 25 30 35 40 45 50 55 60 65
- 10 T will make two revolutions for each revolution of the gear N. The rows of keys C' occupy one-third of the circles in which they are located, and the numbers upon the wheel T occupy two-thirds of the circle in which they are located. The travel of the end of the bar I' over the entire length of the rows of keys will cause the wheel T to make two-thirds of a revolution, while a half-revolution of the bar I' will cause the wheel T to make a full revolution. This arrangement permits the numbers upon the wheel T to be made larger than if that wheel made but one revolution for each revolution of the bar I' and gear N.
- 15 20 25 30 35 40 45 50 55 60 65
- 25 The arrangement of the keys in two concentric rows co-operating with a single latch-bar I' enables a larger number of keys to be employed in a given space than when they are arranged in a single row, as in my prior patents before referred to. Thirty keys instead of twenty might readily be employed in my present machine by making the two rows of keys extend over one-half of the circles in which they are placed. In such case
- 30 35 40 45 50 55 60 65
- 35 the numbers on the indicator-wheel T would be made to form a complete circle, so that a movement of the bar I' over the entire series of keys would give the indicator one complete revolution.
- 40 45 50 55 60 65
- 40 Having thus fully described my invention, I claim—
1. The combination of a revoluble driving-disk provided with two cam-grooves and a driving-shoulder, a revoluble and radially-movable latch-bar provided with two lugs fitting in the cam-grooves in the driver and alternately co-operating with the driving-shoulder, and a series of stops co-operating with the latch-bar to disconnect its engaged lug from the shoulder of the driver at different points, substantially as described.
- 45 50 55 60 65
5. The combination of the driving-disk E, provided with the two grooves G' and G² and the driving-shoulder K', the toothed plate G³, the radially-sliding and revoluble bar I', having the lugs H' and H² fitting in the grooves G' and G² and alternately co-operating with the driving-shoulder K', and the series of stop-keys C', co-operating with the bar I', substantially as described.
6. The combination of the driving-disk E, provided with the two grooves G' and G² and the driving-shoulder K', the toothed plate G³, the radially-sliding and revoluble bar I', having the two lugs H' and H² fitting in the grooves G' and G² and co-operating alternately with the shoulder K' and toothed plate G³, and the series of keys C', co-operating with the bar I', substantially as described.
7. The combination of the driving-disk E, provided upon one side with the cam-groove L² and on the other side with the two grooves G' and G², and driving-shoulders K' and K², the radially-movable and revoluble bar K, having the stud M fitting in the groove L² and provided with the teeth L and L', the registering-wheel F, with which the teeth L and L' alternately engage, the bar I' upon the opposite side of the disk E, revolving with the bar K, but radially movable independently thereof, the lugs H' and H² on the bar I', fitting in the grooves G' and G² in the disk E and co-operating with the driving-shoulders K' and K², the fixed stop N⁵, co-operating with the bar K and the fixed cam N⁴, and series of keys C', co-operating with the bar I', substantially as described.
8. The combination of the driving-disk E, provided with the grooves L² and G' and G² and driving-shoulders K' and K², the bar K, provided with the stud M, co-operating with the groove L², the teeth L and L', and toothed studs O and O' on the bar K, the fixed locking-disk P, co-operating with the toothed studs O and O', and the registering-wheel F, co-operating with the teeth L and L', the gear N, revolving with the bar K, the bar I', revolving with the bar K and provided with lugs H' and H², fitting in the grooves G' and G² in the disk E, and with cams J² and J³, the fixed stop N⁵, co-operating with the bar K, and the fixed cam N⁴ and keys C', co-operating with the cams J² and J³ on the bar I', substantially as described.
9. The combination of a driver E, having a driving-shoulder K', a radially-movable and revoluble bar I', provided with the two lugs H' and H², alternately co-operating with the

fitting in the cam-grooves and alternately co-operating with the driving-shoulders and toothed plate, a fixed cam co-operating with the latch-bar at the end of the first half of the revolution of the driving-disk to disconnect its engaged lug from one of the shoulders of the disk and co-operating with a series of stops during the second half of the revolution of the driving-disk to disconnect said lug from the other shoulder, substantially as described.

10 15 20 25 30 35 40 45 50 55 60 65

4. The combination of the revoluble driving-disk E, provided with the two grooves G' and G² and driving-shoulder K', the radially-sliding and revoluble bar I', having the lugs H' and H² fitting in the grooves G' and G² and alternately co-operating with the driving-shoulder K', and the series of stop-keys C', co-operating with the bar I', substantially as described.

5. The combination of the driving-disk E, provided with the two grooves G' and G² and the driving-shoulder K', the toothed plate G³, the radially-sliding and revoluble bar I', having the two lugs H' and H² fitting in the grooves G' and G² and co-operating alternately with the shoulder K' and toothed plate G³, and the series of keys C', co-operating with the bar I', substantially as described.

6. The combination of the driving-disk E, provided upon one side with the cam-groove L² and on the other side with the two grooves G' and G², and driving-shoulders K' and K², the radially-movable and revoluble bar K, having the stud M fitting in the groove L² and provided with the teeth L and L', the registering-wheel F, with which the teeth L and L' alternately engage, the bar I' upon the opposite side of the disk E, revolving with the bar K, but radially movable independently thereof, the lugs H' and H² on the bar I', fitting in the grooves G' and G² in the disk E and co-operating with the driving-shoulders K' and K², the fixed stop N⁵, co-operating with the bar K and the fixed cam N⁴, and series of keys C', co-operating with the bar I', substantially as described.

7. The combination of the driving-disk E, provided with the grooves L² and G' and G² and driving-shoulders K' and K², the bar K, provided with the stud M, co-operating with the groove L², the teeth L and L', and toothed studs O and O' on the bar K, the fixed locking-disk P, co-operating with the toothed studs O and O', and the registering-wheel F, co-operating with the teeth L and L', the gear N, revolving with the bar K, the bar I', revolving with the bar K and provided with lugs H' and H², fitting in the grooves G' and G² in the disk E, and with cams J² and J³, the fixed stop N⁵, co-operating with the bar K, and the fixed cam N⁴ and keys C', co-operating with the cams J² and J³ on the bar I', substantially as described.

8. The combination of a driver E, having a driving-shoulder K', a radially-movable and revoluble bar I', provided with the two lugs H' and H², alternately co-operating with the

shoulder K', the keys C', co-operating with the bar and the gear N, revolving with the bar, the pinion N', meshing with the gear N, the pinion N², revolving with the pinion N', the indicator-wheel T, and the gear S, fast thereon and meshing with the pinion N², substantially as described.

9. The combination of a driver E, having a driving-shoulder K', a radially-sliding and revoluble bar I', provided with lugs H' and H², alternately co-operating with the shoulder K', and also provided with the two cams J' and J², each having an arresting-shoulder O², and the series of keys C', co-operating with the cams J' J² and shoulders O², substantially as described.

10. The combination of a revoluble driver, a radially-movable and revoluble bar driven thereby, and two concentric rows of keys co-operating with the bar, substantially as described.

11. The combination of a revoluble driver having a driving-shoulder, a radially-movable and revoluble bar provided with a lug co-operating with the shoulder of the driver, and two concentric rows of keys co-operating with the bar, substantially as described.

12. The combination of a revoluble driver having a driving-shoulder, a radially-movable and revoluble bar provided with a lug co-operating with the driving-shoulder, and a fixed cam and two concentric rows of movable cams or keys co-operating with the bar, substantially as described.

13. The combination of a revoluble driver, a revoluble wheel, a revoluble latch for connecting them, and two concentric rows of keys co-operating with the latch to disconnect them.

14. The combination of a revoluble driver, a revoluble registering-wheel, a latch for connecting them at the end of the first half of the revolution of the driver, a series of stops for disconnecting them during the second half of the revolution of the driver, and a lock actuated by the driving mechanism to lock the registering-wheel at the beginning of the first half of the revolution of the driver and to unlock it at the end of said half-revolution.

15. The combination of a revoluble driver, a revoluble indicator-wheel, and a revoluble registering-wheel, a latch for connecting the driver and indicator-wheel during the first half of the revolution of the driver, and a cam co-operating with the latch at the end of said half-revolution to cause it to connect the driver and registering-wheel, a series of stops co-operating with the latch during the second half of the revolution of the driver to disconnect the driver from both the indicator and registering wheels, and a lock actuated by the driving mechanism to lock the registering-wheel at the beginning of the first half of the revolution of the driver and to unlock it at the end of said half-revolution.

16. The combination of the locking-ratchet

I, revolving with the registering-wheel, the revoluble disk Z, provided with the cam-groove Y, and the bar U, provided with the stud X, co-operating with the cam-groove Y, and with the locking-tooth W, co-operating with the ratchet I, substantially as described.

17. The combination of a revoluble driver, a revoluble wheel, a revoluble latch for connecting them, a series of stops co-operating with the latch to disconnect them, and a lock for the driver, actuated by the operation of a key to release the driver and operating automatically to lock the driver again at the completion of its revolution.

18. The combination of a revoluble shaft, a driver fast thereon, a revoluble wheel loose thereon, a latch for connecting them, a series of keys co-operating with the latch to disconnect them, a locking-disk revoluble with the driver, a locking-dog co-operating therewith to lock the driver from movement and actuated by the operation of any one of the keys to release the driver.

19. The combination of a revoluble shaft, a driver fast thereon, a revoluble wheel loose thereon, a latch for connecting them, a series of shouldered keys co-operating with the latch to disconnect them, a detent-plate moved by the operation of any one of the keys and co-operating with the shoulder of the key to hold the key in operated position, a locking-disk fast upon the shaft, and a locking-dog co-operating with the disk and actuated by the movements of the detent-plate to lock the driver from movement, except when one of the keys is operated.

20. The combination of a revoluble driver, a revoluble wheel, a revoluble latch for connecting them, a series of shouldered keys co-operating with the latch to disconnect them, a movable detent-plate co-operating with the shoulders of the keys to detain them in operated position and moved by the driving mechanism at the completion of the revolution of the driver to release the operated key.

21. The combination of a revoluble driver, a revoluble wheel, a latch for connecting them, a series of shouldered keys co-operating with the latch, a movable detent-plate co-operating with the shoulders of the keys to detain them in operated position, and a cam actuated by the driving mechanism and co-operating with the detent-plate to move the same and release the operated key at the end of the revolution of the driver.

22. The combination of a revoluble shaft, a driver fast thereon, a wheel loose thereon, a latch for connecting them, a series of shouldered keys co-operating with the latch to disconnect them, a movable detent-plate co-operating with the shoulders of the keys to detain them in operated position, and a cam fast upon the revoluble shaft and actuating the detent-plate to release the operated key at the completion of the revolution of the driver.

23. The combination of a revoluble driver, a revoluble indicator, a revoluble latch for

connecting them, a series of stops co-operating with the latch to disconnect them, a casing provided with a reading-opening for the exposure of the numbers upon the indicator, and an automatic screen actuated by the driving mechanism to open and close the reading-opening to alternately expose and hide the numbers on the indicator.

24. The combination of a revolute shaft, a driver fast thereon, a revolute wheel loose thereon, a latch for connecting them, a series of stops co-operating with the latch, a casing

provided with a reading-opening for the exposure of the numbers on the indicator, a screen movable back and forth between the reading-opening and indicator to alternately hide and expose the numbers on the latter, and a cam fast upon the revolute shaft and co-operating with the screen.
